Industry Co., Ltd., Osaka, Japan

Filed Aug. 12, 1966, Ser. No. 3,446

Term of patent 14 years

(Cl. D90—20)

FIG. 1

FIG. 2

FIG. 3

FIG. 5

FIG. 4

FIG. 1 is a fragmentary perspective view of a tire showing my new design;

FIG. 2 is a fragmentary perspective view of the other side;

FIG. 3 is a sectional view;

FIG. 4 is a fragmentary side view; and

FIG. 5 is a perspective view of the tire, it being understood that the full line portion is repeated throughout the circumference of the tire shown by means of broken lines.

The dominant features of my design reside in those portions shown in full lines in the drawings.

I claim:

The ornamental design for a tire, substantially as shown and described.
